WELL PUMPING DEVICE

Albert Bullock, El Monte, Calif.

Refiled for abandoned application Serial No.
614,525, May 31, 1932. This application
August 24, 1936, Serial No. 97,663

16 Claims. (Cl. 74—29)

My invention relates to mechanism for reciprocating sucker rods employed in the operation of well pumps, and relates particularly to a simple and efficient mechanism especially adapted for use with oil well pumps.

It is an object of the invention to provide a pumping device having a lifting member adapted to be secured to the upper end of a string of sucker rods of a well pump, together with means 10 for exerting a lifting force to raise the sucker rods and the pump piston through a pumping stroke, means for releasing the application of lifting force and means for controlling the downward movement of the sucker rods and piston 15 during the return stroke thereof.

A further object of the invention is to provide a mechanism of the above character especially adapted for operation of long stroke pumps with a minimum expenditure of power and maximum efficiency. In a preferred form of the invention the operation of the pump is accomplished through use of a pinion gear engaging a rack which is vertically guided, and in which the 20 weight of the pump parts is counterbalanced by 25 a second rack which engages the pinion and has counterweights secured thereto.

It is a further object of the invention to provide a pumping device having means which operates at the end of the return stroke to initiate 30 the succeeding pumping stroke.

Further objects and advantages of the invention will be set forth in the following part of the specification.

Referring to the drawings which are for illustrative purposes only,

Fig. 1 is a partly sectioned elevational view of a preferred form of my invention.

Fig. 2 is an enlarged fragmentary cross-section on a plane represented by the line 2—2 of Fig. 1. 40 Fig. 3 is a partly sectioned elevational view of an alternative form of the invention in which a chain and sprocket are employed instead of a rack and gear as illustrated in Fig. 1.

Fig. 4 is a plan view corresponding to Fig. 3. 45 In the preferred form of my invention shown in Figs. 1 and 2, I employ a supporting structure 11 which may be of tripod type having angle-iron legs 12 joined to a top structure 13 and having an intermediate platform 14 provided with a leftward extension 15 for supporting a motor 16 which through a belt, chain, or chain-belt 16a drives a wheel 17 mounted on a shaft 18. On the shaft 18 rearwardly of the wheel 17 is a pinion 20 which drivably engages a relatively large gear 50

21 mounted on a main shaft 22 which is carried in ball bearings 23, as shown in Fig. 2, carried in turn in bearing receptacles 24 of a housing 25. The housing 25 is preferably mounted on the platform 14 and provides vertical guide means 26 for a lifting means or motivating member 27 of bar-form having leftwardly faced rack teeth 28 which engage a pinion 30 on the main shaft 22 within the housing 25.

The lower end 31 of the member 27 is equipped with a clevis 32 which connects to the upper end of a sucker rod string 33 extending down to a pump secured in a well, not shown. The upper end 34 of the member 27 is secured to a rod 35 which extends upwardly through a tube or sleeve 36 which in turn extends through a packing box 27a in the lower end of a cylinder 38 and connects to a piston 40 vertically slidable in the cylinder 38. The rod 35 has lower stop means 41 thereon in the form of nuts adapted to engage the lower end of the tube 36, and upper stop means 42 in the form of nuts adapted to engage the upper end of the tube 36.

Adjacent the member 27 and on the opposite side of the pinion 30 is a counterbalance means 43 having a rack 44 vertically slidable in the leftward portion of the housing 25 and having leftwardly extending arms or brackets 45 and 46 at the ends thereof for supporting a vertical bar 47 on which an assembly of counterweights 48 is carried. By means of ball bearings 50 supported in the housing 25 as shown in Fig. 2, rollers 51 are held against the outer faces of the members 27 and 44 to hold them in operative engagement with the pinion 30 with a minimum of frictional resistance. A switch lever 53 for operating a switch 54 is connected to the lower end of a vertical rod 55, the upper end of this rod 55 being slidable in a bracket 56. Adjustably secured to the rod 55 are fingers 56 and 57 adapted to be engaged by lugs 58 and 60 projecting rightwardly from the respective upper and lower ends of the member 27. From the switch means 54 a conduit 61 is extended to the motor 16 for the electrical connections to the motor 16, and a conduit 62 is shown for carrying electric lead wires to the switch means 54 from a suitable source of electric power.

The pumping device is shown in Fig. 1 at the start of a pumping stroke. The dog 58 has engaged the finger 56 and has forced the rod 55 down and thus has actuated the switch means 54 to on position, causing energization of the motor 16 with the result of driving the pinion 30 in anti-clockwise direction to lift the motivat- 55

ing member 27. As the bar 35 moves upwardly the nuts 41 engage the lower end of the sleeve or tube 36, raising the piston 40 within the cylinder 38. The lug 60 then engages the finger 57 and raises the rod 55, moving the lever 53 of the switch means 54 to off position and stopping the supply of electric energy to the motor 16. As soon as the inertia in the moving parts, such as 17 and 21, is overcome, the return stroke 10 of the mechanism starts. As the rod 35 is carried downwardly, the stop means 42 thereon engages the upper end of the tube 36, and the piston 40 is carried downwardly, compressing air or other fluid in the lower part of the cylinder 15 38 and bringing the rod 35 and its suspended parts to a cushioned stop after the lug 58 has re-engaged the finger 56 to actuate the switch means and cause a re-electrification of the motor 16.

20 The compressed fluid in the cylinder 38 constitutes a resilient means exerting an upward force tending to raise the piston 40 and the therefrom suspended parts, and to initiate or assist in initiating the succeeding pumping stroke 25 of the mechanism as the power of the motor 16 is delivered through the pinion 30 to the member 27. The continued operation of the pumping device is a succession of the individual operations above described, there being no consumption of 30 power during the return strokes. The moving parts, such as 27, 35, and 44, may be readily proportioned to produce the desired length of pumping stroke.

The form of the invention shown in Figs. 1 35 and 2 is especially suited for long stroke pumps in deep settings. In Figs. 3 and 4, I show a form of the invention adapted for pumps of any stroke set in shallow wells. On a suitable base 70 a standard 71 rotatably supports a shaft 72 which 40 has a flywheel or pulley 73 at one end thereof adapted to be driven from a suitable power source, such as a gasoline engine, by means of a belt, not shown. On the forward end of the shaft 72 is a drive member 74, such as a pulley, 45 having a clutch mechanism 75 therein for detachably connecting it to the shaft 72, this clutch mechanism being thrown in and out of engagement by a clutch yoke 76 pivoted on a vertical pin 77 and having a forwardly extending 50 lever 78 connected by a link 80 to the upper end of a lever 81 which projects upwardly from a horizontal shaft 82 mounted in a support 83. A driving loop, such as a belt 84, connects the pulley 74 to a pulley 85 mounted on a jack shaft 55 86 carried at the left side of the base 70 by bearings 87. A pinion 88 keyed to the shaft 86 adjacent to the pulley 85 is adapted to drive a gear 90 mounted on a main shaft 91 carried in bearings 92. Between the bearings 92 a sprocket 60 93 is keyed on the shaft 91 and carries a sucker rod motivating means in the form of a chain 94 having means 95 at its leftward end for securing 65 it to a sucker rod string 96. The rightward portion 97 of the chain 94 is carried over an idler sprocket 98 loosely mounted on the jack shaft 86, and is extended down through an opening 100 in the base 70 to a supporting plate 101 adapted to receive counter weights 102. A spring 104 is employed between the counter weights 70 102 and the base 70 to bring the mechanism to a cushioned stop at the end of each return stroke.

In Fig. 3 the alternative form of the invention is shown with the motivating means or chain 94 at the end of its return stroke. At this time 75 the spring 104 is compressed and is exerting

a force to initiate or to assist in initiating a power stroke, and a lug 107 on the rear end of the chain 94 has lifted a lever 108 secured to the forward end of the shaft 82, causing a rightward movement of the lever, which movement is transmitted through the link 80 to the lever 78, causing the shifting yoke 76 to swing rearwardly and carry the engagement parts of the clutch mechanism 75 to engage and thereby transmit power through the belt 84 and the gears 10 88 and 90 to the sprocket 93, to produce a clockwise rotation thereof for lifting the leftward portion of the chain 94. This movement of the chain 94 is continued until a lug 109 on the leftward portion of the chain 94 engages the lever 15 108 and swings it downwardly so as to produce a disengagement of the clutch mechanism 75, to leave the weight of the pump parts and the sucker rod string 96 to accomplish a return stroke of the mechanism.

20 Although I have disclosed practical and operative forms of my invention, it is recognized that many of the parts or elements thereof may be readily replaced by other parts of equivalent function; therefore the invention is in no way 25 limited to the details disclosed herein, but should be limited only by the hereinafter set forth claims.

This application is a refiled of my abandoned application, Serial No. 614,525, filed May 31, 30 1932, and entitled "Well pumping devices".

I claim as my invention:

1. A pumping device of the character described, for use with a pump having a reciprocable operating member extending upwardly therefrom, including: a motivating member adapted to reciprocatory movement; means for operatively supporting said motivating member; mechanism for moving said motivating member through an operating stroke in a direction to produce a pumping stroke of said operating member; power means adapted to exert force in said mechanism to move said motivating member in said direction; and means controlled automatically in accordance with the position of said motivating member for discontinuing the transmission of power by said power means to said mechanism when said motivating member arrives at a position near the end of its operating stroke and re-establishing transmission of power by said power means to said mechanism when said motivating member is at a position near the start of its operating stroke, there being means for applying potential forces to move said motivating member in direction reverse to said operating stroke when said transmission of power is discontinued.

2. A device as defined in claim 1, in which said controlled means is adjustable to vary the positions of said motivating member at which said transmission of power will be discontinued and reestablished.

3. A pumping device of the character described, for use with a pump having a reciprocable operating member extending upwardly therefrom, including: a motivating member adapted to reciprocatory movement; means for operatively supporting said motivating member; mechanism for moving said motivating member through an operating stroke in a direction to produce a pumping stroke of said operating member; power means adapted to exert force in said mechanism to move said motivating member in said direction; means controlled automatically in accordance with the position of said motivating member for discontinuing the transmission of

power by said power means to said mechanism when said motivating member arrives at a position near the end of its operating stroke and reestablishing transmission of power by said power means to said mechanism when said motivating member is at a position near the start of its operating stroke, there being means for applying potential forces to move said motivating member in direction reverse to said operating stroke when said transmission of power is discontinued; and resilient means connected to said motivating member to apply a stopping reaction to the reverse movement of said motivating member.

4. A pumping device of the character described, for use with a pump having a reciprocable operating member extending upwardly therefrom, including: a motivating member adapted to reciprocatory movement; means for operatively supporting said motivating member; mechanism for moving said motivating member through an operating stroke in a direction to produce a pumping stroke of said operating member; power means adapted to exert force in said mechanism to move said motivating member in said direction; means controlled automatically in accordance with the position of said motivating member for discontinuing the transmission of power by said power means to said mechanism when said motivating member arrives at a position near the end of its operating stroke and reestablishing transmission of power by said power means to said mechanism when said motivating member is at a position near the start of its operating stroke, there being means for applying potential forces to move said motivating member in direction reverse to said operating stroke when said transmission of power is discontinued; and resilient means connected to said motivating member to apply a stopping reaction to the reverse movement of said motivating member and to initiate the successive operating strokes of said motivating member.

5. A pumping device of the character described, for use with a pump having a reciprocable operating member extending upwardly therefrom, including: a motivating member adapted to reciprocatory movement; means for operatively supporting said motivating member; mechanism for moving said motivating member through an operating stroke in a direction to produce a pumping stroke of said operating member; power means adapted to exert force in said mechanism to move said motivating member in said direction; means controlled automatically in accordance with the position of said motivating member for discontinuing the transmission of power by said power means to said mechanism when said motivating member arrives at a position near the end of its operating stroke and reestablishing transmission of power by said power means to said mechanism when said motivating member is at a position near the start of its operating stroke, said motivating member being moved by potential forces in direction reverse to said operating stroke when said transmission of power is discontinued; and dash-pot means connected to said motivating member to control the reverse movement of said motivating member.

6. A pumping device of the character described, for use with a pump having a reciprocable operating member extending upwardly therefrom, including: a motivating member adapted to reciprocatory movement; means for opera-

tively supporting said motivating member; mechanism for moving said motivating member through an operating stroke in a direction to produce a pumping stroke of said operating member; power means adapted to exert force in said mechanism to move said motivating member in said direction; means controlled automatically in accordance with the position of said motivating member for discontinuing the transmission of power by said power means to said mechanism when said motivating member arrives at a position near the end of its operating stroke and reestablishing transmission of power by said power means to said mechanism when said motivating member is at a position near the start of its operating stroke, said motivating member being moved by potential forces in direction reverse to said operating stroke when said transmission of power is discontinued; and dash-pot means connected to said motivating member to control the reverse movement of said motivating member and to initiate the successive operating strokes of said motivating member.

7. A pumping device of the character described, for use with a pump having a reciprocable operating member extending upwardly therefrom, including: a motivating member adapted to reciprocatory movement; means for operatively supporting said motivating member; mechanism for moving said motivating member through an operating stroke in a direction to produce a pumping stroke of said operating member; an electric motor adapted to exert force in said mechanism to move said motivating member in said direction; and means controlled automatically in accordance with the position of said motivating member for shutting down the supply of electric energy to said motor when said motivating member arrives at a position near the end of its operating stroke and reestablishing the supply of electric energy to said motor when said motivating member is at a position near the start of its operating stroke, there being means for applying potential forces to move said motivating member in direction reverse to said operating stroke when the supply of electric energy to said motor is shut down.

8. A pumping device of the character described, for use with a pump having a reciprocable operating member extending upwardly therefrom, including: a motivating member adapted to reciprocatory movement; means for operatively supporting said motivating member; mechanism for moving said motivating member through an operating stroke in a direction to produce a pumping stroke of said operating member; an electric motor adapted to exert force in said mechanism to move said motivating member in said direction; means controlled automatically in accordance with the position of said motivating member for shutting down the supply of electric energy to said motor when said motivating member arrives at a position near the end of its operating stroke and reestablishing the supply of electric energy to said motor when said motivating member is at a position near the start of its operating stroke, there being means for applying potential forces to move said motivating member in direction reverse to said operating stroke when the supply of electric energy to said motor is shut down; and resilient means connected to said motivating member to apply a stopping reaction to the reverse movement of said motivating member.

9. A pumping device of the character described,

for use with a pump having a reciprocable operating member extending upwardly therefrom, including: a toothed rack forming a motivating member adapted to reciprocatory movement; 5 means for operatively supporting said motivating member; mechanism for moving said motivating member through an operating stroke in a direction to produce a pumping stroke of said operating member, said mechanism including a 10 driving pinion engaging said rack forming said motivating member; power means adapted to exert force in said mechanism to move said motivating member in said direction; and means controlled automatically in accordance with the 15 position of said motivating member for discontinuing the transmission of power by said power means to said mechanism when said motivating member arrives at a position near the end of its operating stroke and reestablishing transmission 20 of power by said power means to said mechanism when said motivating member is at a position near the start of its operating stroke, there being means for applying potential forces to said motivating member in direction reverse to said operating stroke when said transmission of power is 25 discontinued.

10. A pumping device of the character described, for use with a pump having a reciprocable operating member extending upwardly therefrom, including: a toothed rack forming a motivating member adapted to reciprocatory movement; means for operatively supporting said motivating member; mechanism for moving said motivating member through an operating stroke 30 in a direction to produce a pumping stroke of said operating member, said mechanism including a driving pinion engaging said rack forming said motivating member; an electric motor adapted to exert force in said mechanism to move said motivating member in said direction; and means controlled automatically in accordance with the 35 position of said motivating member for shutting down the supply of electric energy to said motor when said motivating member arrives at a position near the end of its operating stroke and reestablishing the supply of electric energy to said motor when said motivating member is at a position near the start of its operating stroke, there being means for applying potential forces to move said motivating member in direction reverse to said operating stroke when the supply of electric energy to said motor is shut down.

11. A pumping device of the character described, for use with a pump having a reciprocable operating member extending upwardly therefrom, including: a toothed rack forming a motivating member adapted to reciprocatory movement; means for operatively supporting said motivating member; mechanism for moving said motivating member through an operating stroke in a direction to produce a pumping stroke of said operating member, said mechanism including a driving pinion engaging said rack forming said motivating member; power means adapted to exert force in said mechanism to move said motivating member in said direction; means controlled automatically in accordance with the position of said motivating member for discontinuing the transmission of power by said power means to said mechanism when said motivating member arrives at a position near the end of its operating stroke and reestablishing transmission of power by said power means to said mechanism when said motivating member is at a position 70 near the start of its operating stroke, there being means for applying potential forces to move said motivating member in direction reverse to said operating stroke when said transmission of power is discontinued; a counterbalance having teeth engaging said drive pinion; and guide means for said counterbalance.

12. A pumping device of the character described, for use with a pump having a reciprocable operating member extending upwardly therefrom, including: a toothed rack forming a motivating member adapted to reciprocatory movement; means for operatively supporting said motivating member; mechanism for moving said motivating member through an operating stroke in a direction to produce a pumping stroke of said operating member, said mechanism including a driving pinion engaging said rack forming said motivating member; power means adapted to exert force in said mechanism to move said motivating member in said direction; means controlled automatically in accordance with the 10 position of said motivating member for discontinuing the transmission of power by said power means to said mechanism when said motivating member arrives at a position near the end of its operating stroke and reestablishing transmission of power by said power means to said mechanism when said motivating member is at a position near the start of its operating stroke, there being means for applying potential forces to move said motivating member in direction reverse to said operating stroke when said transmission of power is discontinued; and resilient means connected to said motivating member to apply a stopping reaction to the reverse movement of said motivating member and to initiate the successive operating strokes of said motivating member. 15

12. A pumping device of the character described, for use with a pump having a reciprocable operating member extending upwardly therefrom, including: a toothed rack forming a motivating member adapted to reciprocatory movement; means for operatively supporting said motivating member; mechanism for moving said motivating member through an operating stroke in a direction to produce a pumping stroke of said operating member, said mechanism including a driving pinion engaging said rack forming said motivating member; power means adapted to exert force in said mechanism to move said motivating member in said direction; means controlled automatically in accordance with the 20 position of said motivating member for discontinuing the transmission of power by said power means to said mechanism when said motivating member arrives at a position near the end of its operating stroke and reestablishing transmission of power by said power means to said mechanism when said motivating member is at a position near the start of its operating stroke, there being means for applying potential forces to move said motivating member in direction reverse to said operating stroke when said transmission of power is discontinued; and resilient means connected to said motivating member to apply a stopping reaction to the reverse movement of said motivating member. 25

13. A pumping device of the character described, for use with a pump having a reciprocable operating member extending upwardly therefrom, including: a toothed rack forming a motivating member adapted to reciprocatory movement; means for operatively supporting said motivating member; mechanism for moving said motivating member through an operating stroke in a direction to produce a pumping stroke of said operating member, said mechanism including a driving pinion engaging said rack forming said motivating member; power means adapted to exert force in said mechanism to move said motivating member in said direction; means controlled automatically in accordance with the position of said motivating member for discontinuing the transmission of power by said power means to said mechanism when said motivating member arrives at a position near the end of its operating stroke and reestablishing transmission of power by said power means to said mechanism when said motivating member is at a position near the start of its operating stroke, there being means for applying potential forces to move said motivating member in direction reverse to said operating stroke when said transmission of power is discontinued; a counterbalance having teeth engaging said drive pinion; and guide means for said counterbalance. 30

14. A pumping device of the character described, for use with a pump having a reciprocable operating member extending upwardly therefrom, including: a toothed rack forming a motivating member adapted to reciprocatory movement; means for operatively supporting 35

- said motivating member; mechanism for moving said motivating member through an operating stroke in a direction to produce a pumping stroke of said operating member, said mechanism including a driving pinion engaging said rack forming said motivating member; an electric motor adapted to exert force in said mechanism to move said motivating member in said direction; means controlled automatically in accordance with the position of said motivating member for shutting down the supply of electric energy to said motor when said motivating member arrives at a position near the end of its operating stroke and reestablishing the supply of electric energy to said motor when said motivating member is at a position near the start of its operating stroke, there being means for applying potential forces to move said motivating member in direction reverse to said operating stroke 10 when the supply of electric energy to said motor is shut down; a counterbalance having teeth engaging said drive pinion; and guide means for said counterbalance.
15. A pumping device of the character described, for use with a pump having a reciprocal operating member extending upwardly therefrom, including: a motivating member adapted to reciprocatory movement; means for operatively supporting said motivating member; mechanism for moving said motivating member through an operating stroke in a direction to produce a pumping stroke of said operating member; power means adapted to exert force in said mechanism to move said motivating member in said direction; a clutch for transmitting motion from said power means to said mechanism; and means controlled automatically in accordance with the position of said motivating member for releasing said clutch when said motivating member arrives at a position near the end of its operating stroke and reengaging said clutch when said motivating member is at a position near the start of its operating stroke, there being means for applying potential forces to move said motivating member in direction reverse to said operating stroke 20 when said transmission of power is discontinued. 25
20. A pumping device of the character described, for use with a pump having a reciprocal operating member extending upwardly therefrom, including: a link chain; a motivating member adapted to reciprocatory movement; means for operatively supporting said motivating member; mechanism for moving said motivating member through an operating stroke in a direction to produce a pumping stroke of said operating member, said mechanism including sprocket means engaging said chain; power means adapted to exert force in said mechanism to move said motivating member in said direction; and means controlled automatically in accordance with the position of said motivating member for discontinuing the transmission of power by said power means to said mechanism when said motivating member arrives at a position near the end of its operating stroke and reestablishing transmission 25 of power by said power means to said mechanism when said motivating member is at a position near the start of its operating stroke, there being means for applying potential forces to move said motivating member in direction reverse to said operating stroke when said transmission of power is discontinued. 30
